CANDLE HOLDER

James D. Boyd, 3231 Washington Ave.,
St. Joseph, Mich. 49085

Filed July 19, 1972, Ser. No. 273,180

Term of patent 14 years

Int. Cl. D26—01

U.S. Cl. D48—2

Fig. 5

FIG. 1 is a perspective view of a candle holder showing my new design.

FIG. 2 is a top plan view of the candle holder.

FIG. 3 is a view of the candle holder in side elevation.

FIG. 4 is a view of the candle holder in side elevation as seen 90 degrees displaced from FIG. 3.

FIG. 5 is a transverse sectional view taken on line 5—5 of FIG. 3.

I claim:

The ornamental design for a candle holder, as shown.
